(57) **CLAIM**

What is claimed is the ornamental design for a hitch adapter, as shown.

DESCRIPTION

FIG. 1 shows an isometric view of a hitch adapter according to a first embodiment.

FIG. 2 shows an enlarged front plan view of a hitch adapter according to the first embodiment.

FIG. 3 shows an enlarged back plan view of a hitch adapter according to the first embodiment.

FIG. 4 shows a right side plan view, the left side being a mirror image thereof, of a hitch adapter according to the first embodiment.

FIG. 5 shows a top plan view, the bottom plan view being a mirror image thereof, of a hitch adapter according to the first embodiment.

FIG. 6 shows an isometric view of a hitch adapter according to a second embodiment.

FIG. 7 shows an enlarged front plan view of a hitch adapter according to the second embodiment.

FIG. 8 shows an enlarged back plan view of a hitch adapter according to the second embodiment.

FIG. 9 shows a right side plan view, the left side being a mirror image thereof, of a hitch adapter according to the second embodiment; and,

FIG. 10 shows a top plan view, the bottom plan view being a mirror image thereof, of a hitch adapter according to the second embodiment.
